SODA FOUNTAIN DRAFT HEAD

Frank H. Beall, Detroit, Mich.; Lois Viola Brown
 Beall, executrix of said Frank H. Beall, deceased, assignor to John A. Maxwell, Detroit, Mich.

Application August 9, 1946, Serial No. 689,566

25 Claims. (Cl. 137—636)

1

This invention relates to means for dispensing charged water, that is, water charged with CO₂ gas at soda fountains.

The soda water valve has always presented a particular valve problem as it operates under high pressure and has to operate in one direction to give a broken stream of soda water to fill the glass rapidly and in the other direction to give a fine high speed jet of soda water to mix the solution and produce a foam. This problem is further complicated by the fact that movement of the handle in either direction from the off position to the on position is limited and produces a difficult sealing problem.

A valve in common use today brings the soda water under pressure through the valve casing to a centered hole in a washer against which is pressed a metal disk arranged to be rotated by the handle. A passage is provided in this disk which connects the centered hole with an outlet hole adjacent the edge of the disk. Circumferentially spaced on either side of this latter hole are two holes in the washer which are connected by passages in the casing to the nozzle. When the handle is moved forwardly, the disk rotates to connect the centered hole supplying the soda water through the passage in the disk with the passage in the casing for giving a broken stream of soda water; and on moving the handle backward, the passage in the disk connects the centered hole with the passage in the casing to the jet. The pressure between the rotatable metal disk and the washer is obtained by screwing into the casing a plug having a rounded face which bears against the disk and permits the rotation on the principle of a ball-and-socket joint. The difficulty with this valve, as well as all others in use today, is that with any wear of the leather washer the valve starts to leak and has to be adjusted, and at very frequent intervals.

The object of this invention is to provide a self-adjusting valve which, when connected into the system, will remain leakproof during the life of the washer.

A second object of this invention is to provide a valve for a soda fountain system that can be easily assembled and readily disassembled whenever it is necessary to change washers.

A third object of the invention is to provide a valve easily made of stainless steel.

A fourth object of this invention is to combine two of these valves to be operated by a single handle using one valve to deliver the soda water and the second valve to deliver a flavored sirup from a sirup container.

2

A fifth object is to use water, as from the city water supply, and provide a carbonator to charge the water with CO₂ gas as it goes to a valve in the draft head, a second valve in said draft head connected to a container having sirup under pressure and a single handle to operate the valves to simultaneously supply sirup and charged water to the nozzle on the forward movement of the handle.

10 A sixth object of the invention is to supply a container, which is readily opened and easily sealed, with a source of fixed reduced CO₂ pressure, so that the amount of sirup per operation of the valve can be regulated.

15 In the drawings:

Figure 1 is a fragmentary front elevational view of a soda fountain draft head, embodying the invention, the operating handle of the head being removed and parts thereof being broken away and shown in section for clearness of illustration.

Figure 2 is a side elevational view with parts in section along the line 2—2 of Figure 1;

Figure 3 is a front elevational view of a modified form of the valve where all the parts are assembled from the operating side, parts being broken away and shown in section for clearness of illustration;

Figure 4 is a front view, partly in elevation and partly in section, showing two valves operated by a single handle to simultaneously supply sirup and soda water; and

Figure 5 is a diagrammatic view showing the component parts of the soda fountain system.

In the drawings, wherein for the purpose of illustration is shown a preferred embodiment of the invention, the numeral 1 designates a generally barrel-shaped stainless steel valve casing having an elongated supporting neck 100 and an internal cylindrical chamber 12. The latter opens 40 through a countersink 6 in one side of the casing 1 and is normally closed by a threaded plug 21. A sealing gasket 8 behind plug 21 prevents fluid from leaking past the threads and makes chamber 12 fluidtight. Charged water under pressure flows into chamber 12 through a pipe 35 in neck 100 and discharges therefrom through passages 29 and 32 to a nozzle 31 which is provided with the usual cup 30 for supplying a low pressure, broken stream and a jet 33 for providing a high pressure, concentrated stream. It will be observed that passage 29 discharges into cup 30 and that passage 32 discharges into jet 33.

As suggested, this invention is concerned primarily with internal valve mechanism for controlling passages 29 and 32, which mechanism

can be easily assembled or disassembled, maintains an efficient seal for relatively long periods of time, and does not require frequent adjustment or replacement of parts. According to the present invention the internal valve mechanism comprises a pivot having a relatively large cylindrical portion 9 which is journaled in a socket 11 provided centrally in the closed side of chamber 12 and a relatively small terminal shank portion 9' which is journaled in a socket 6' provided in the casing 1 behind and concentric to socket 11. Intermediate portions 9 and 9' of the pivot are formed with an integral square portion 10, and casing 1 is provided with an inwardly tapered radial slot 2 which accommodates the valve actuating arm 3 of an operating handle 4. It will be observed that slot 2 extends inwardly past the pivot and that actuating arm 3 is provided at its inner end with an enlarged section having a square opening 7 which receives and snugly fits the square pivot portion 10. Thus the pivot is rocked back and forth by manually pulling handle 4 downwardly or pushing it upwardly on the casing 1. By providing spaced bearings 11 and 6' for the pivot and fastening 20 actuating arm 3 thereto intermediate the bearings the pivot is better able to sustain side thrust against the handle 4. Manifestly, considerable leverage can be imposed on the pivot by lateral pressure on the handle 4, and, if the pivot is not 25 solidly supported, this leverage causes rapid wear of the pivot journals and bearings and also reduces the life of parts carried or actuated by the pivot.

Disposed side by side in the chamber 12 is a disk-shaped washer 15 and a pressure plate 17, the former confined between the pressure plate and the inner radial wall of the chamber and both the washer and pressure plate peripherally engaging the outer annular wall of the chamber 12 as indicated at 16. Washer 15 preferably is made of leather saturated with wax but may be of any suitable material that yields under pressure and is inherently resilient. The pivot portion 9 extends through washer 15 and abuts the radial confronting face of plate 17. Formed integrally on the projecting end of pivot portion 9 is a flat-sided, axially extending tang 18 which enters a correspondingly shaped socket formed in pressure plate 17, which affords a universal joint action but rotatably locks the pivot to pressure plate 17. Thus, the pressure plate 17 rocks back and forth with the pivot, and it has an opening 26 which aligns with orifice 27 for passage 29 when handle 4 is in the extreme forward position, is aligned with orifice 28 for passage 32 when the handle is in the extreme rearward position, and is disposed between the two passages as shown in Figure 2 when the handle is in neutral position. Washer 15 is fastened to the casing 1 by pin 25 (Figure 2) and is provided with holes 27 and 28 which register with orifices 27 and 28 respectively, so that fluid in the chamber 12 may be directed either into passage 29 or into passage 32 or retained in the chamber by selectively positioning the handle 4. Alternatively, the washer 15 may be fastened to pressure plate 17, in which event it would merely be provided with a single hole in register with opening 26.

Pressure plate 17 is axially movable in the chamber 12 so that fluid pressure against its outer face compresses the washer 15. Thus, pressure against the washer 15 increases directly as the pressure in chamber 12 increases. Also,

clearance is provided behind portions 9 and 9' of the pivot so that the latter shifts axially under pressure against plate 17; but it will be readily apparent that this movement is slight and does not in any way affect the efficacy of the pivot support. In effect, however, the cross-sectional area of washer 15 is reduced by the area of pivot portion 9, and the hydrostatic pressure in the washer is increased proportionately. In this manner the hydrostatic pressure in washer 15 is always greater than the fluid pressure against pressure plate 17, and an efficient seal between opening 26 and passages 29 and 32 is assured at all times when handle 4 is in neutral position, as well as the seal of the flow of liquid from chamber 12 to radial slot 2.

In order to assure proper positioning of the pivot, the latter is constantly urged against the pressure plate 17 by a small spring 20 which is disposed in socket 6' behind the pivot portion 9'; and, to prevent this spring from reducing the sealing effect of washer 15 at low pressures, its action is overcome by a relatively larger spring 23 confined between plug 21 and a follower 24 which in turn presses against the outer face of the pressure plate.

In operation, the operator pulls the handle 4 forwardly to register opening 26 with hole 27 to allow the soda water to flow down passage 29 to cup 30, which breaks up the jet effect and provides a broken stream of soda water, and, on pushing the handle back, registers hole 26 with hole 28 and allows the soda water to flow down passage 32 to jet nozzle 33.

Water is charged with CO₂ gas in a carburetor 103 (Figure 5) and thence passes to chamber 12 through pipes 102 (Figure 5) and 35 (Figure 2).

In Figure 3 I have shown an alternative form 40 of the valve where all the parts are assembled from the operating side. In this modification similar parts are given similar numbers with Figures 1 and 2. In this form there is provided a casing 1 in which is drilled a stepped hole 50—50'.

45 Into hole 50' there are fitted spring 23 and follower 24. Pressure plate 51, which is integral with stem 52, is next inserted. On stem 52 is mounted washer 15 which is pinned to metal washer 53 by pins 25. Metal washer 53 is fixed against rotation with casing 1 by a key, not shown. Washer 53 is positioned against axial movement by plug 54 which has a centered hole to accommodate stem 52. Handle 55 is then positioned on one side by bearing plug 56 and on the other by bearing plug 57. Member 58 is next 55 inserted and is keyed to the handle 55 by key 59 and positioned by plug 60. Member 58 is connected to stem 52 to provide rotary movement by tang 18 and clearance is provided between stem 52 and member 58 to accommodate any wear on washer 15.

In this modification, as in the form of the invention shown in Figures 1 and 2, the fitting of the parts is desired to be with reasonable tolerances, that is, a nontight fit, so that the parts can be self-aligning to the slight degree required, which requirement adds to the ease of manufacture of the valve by not requiring highly accurate machine work.

70 In operation, rotation of the handle forward or backward positions opening 26 in pressure plate 51 either to register with hole 27 or hole 28 in the washer 15 as in Figure 2 to provide either a broken stream of soda water from cup 75 30 or a concentrated stream from jet 33.

5

The form of the invention shown in Figure 4 is used for simultaneously dispensing sirup and soda water. In this form there are two valves in casing 1' which are operated by the valve turning means 3' located in the cutaway portion 2' in the casing 1'. In the casing 1' are drilled two stepped holes for the two valves as shown, one from each end and corresponding to countersink 6 and bearing 11 of Figure 1. These valves are complementary and only one of them will be described, the other being given similar numbering. One of the stepped holes 70 forms the cylindrical chamber 71 containing the soda water or sirup, as desired. The inner and smaller hole of the stepped holes forms the bearing for the rotatable member 72 having the squared portion 73 fitting into the square hole in the valve turning means 3'. The partition 74 between the cylindrical chamber 71 and cut-away portion 2' forms one of the closure means for said chamber. Surrounding the controlling member 72 and bearing against closure means 74 is the washer 75. Mounted on the controlling member 72 for rotatable movement therewith by a rounded tongue 76 fitting into groove 77 is a pressure plate 78 which overlies the washer 75. As in Figure 1 the cylindrical chamber 71 is sealed by the plug 21 screwed into threads 22 against the gasket 22', and the pressure plate 78 is biased against the washer 75 by the spring 23 and follower 24. To permit axial movement of the pressure plate 78 in both the right-hand and left-hand valve, there is provided a clearance 79 between the squared portions 73 of the rotatable members 72. A flat spring 80 may be provided if desired to position the controlling members 72 against the pressure plates 78.

In this form of the invention either valve could be used for the soda water, but as shown the soda water under pressure enters the left-hand cylindrical chamber through orifice 81 and the sirup enters the right-hand cavity through orifice 82. The washer 75 is pinned to the cover plate 78 by pins 83 and a hole 84 is provided extending through both the cover plate 78 and the washer 75. In the left-hand valve this hole is located midway between the orifices in the closure means 74 for chamber 71 leading to passages 29 and 32 leading to the nozzle 31 the same as in Figure 1. In the right-hand valve the orifice in the closure means 74 leading to passage 85 is located to register with hole 84 on the forward movement of the handle so that the sirup flows down passage 85 at the same time that the soda water flows down passage 29 to cup 30 to break the jet effect and provide a broken stream of soda water. On the backward movement of the handle only the soda water flows down passage 32 to the jet nozzle 33.

As shown in Figure 5 the valve casing 1' is supported on arm 100 on the soda water cabinet 101. Through this arm passes the tube 102 connected to the orifice 81, Figure 4, in casing 1' with the source of soda water, namely, carbonator 103, which is supplied with water by pump 104 receiving its supply of water from pipe 105 leading to the city water supply.

Orifice 82, Figure 4, in casing 1' communicates with sirup container 109 via tube 106 which passes through arm 100 and leads to needle valve 107 for adjusting the sirup flow and tube 108 which extends to the bottom of the sirup container. Container 109 is equipped with a sealing means comprising a neck 110 provided with a cylindrical portion 111 and a threaded portion 112.

6

112. Screwed into said threaded portion 112 is the wing plug 113. This wing plug is centrally drilled with hole 114 through which passes the bolt 115. Fixed to the bottom of bolt 115 is the disk 116 which slidably fits the cylindrical portion 111 and is separated from wing plug 113 by rubber washer 117. Bolt 115 is provided with threads 118 on which is threaded wing nut 119.

Carbonator 103 is supplied with CO₂ from the cylinder 120 through reduction valve 121 which maintains a constant feed pressure in tube 122 leading to carburetor 103. Leading from tube 122 is a branch tube 123 leading to reduction valve 124 which maintains a greatly reduced pressure in tube 125 which leads to two-way valve 126 and then to container 109 through tube 127. In one direction of operation two-way valve 126 connects tubes 125 and 127 and in the other direction of operation seals tube 125 and vents container 109 to the atmosphere so that it can be opened for filling.

In operation, the cover 130 is removed from the soda water cabinet 101 and valve 126 turned to vent the container 109 to the atmosphere. Wing nut 119 is then loosened and the wing-plug 113 assembly is unscrewed and sirup poured into the container 109. The wing plug 113 is then screwed into place and wing nut 119 screwed up to give an initial set on washer 117. Valve 126 is then turned to connect tubes 125 and 127 and introduce a gas pressure in container 109. Moving valve handle 4 forward permits a flow of sirup through tube 108, needle valve 107, and tube 106, and through the right-hand valve in casing 1' to glass 131. At the same time, soda water from carbonator 103 flows through pipe 102 and through the left-hand valve in casing 1' into the glass 131. On moving the valve handle 4 rearwardly, only a flow of soda water from carbonator 103 through tube 102 and the left-hand valve in casing 1' to glass 131 takes place. This latter provides a jet of soda water to produce the foam on the soda water to be served.

It is to be understood that the form of the invention herewith shown and described is to be taken as the preferred example of the same and that various changes in the size, shape, and arrangement of parts may be resorted to without departing from the spirit of the invention or the scope of the appended claims.

Having thus described the invention, I claim:

1. A soda water faucet for soda water under pressure comprising a valve casing, means in said casing for conducting soda water to a generally cylindrical chamber therein, closure means for the ends of said chamber, a nozzle on said casing, two passages in said casing for conducting said soda water from said chamber to said nozzle, said passages terminating in two spaced orifices in one of said closure means, said spaced orifices being located adjacent the wall of said cylindrical chamber, a valve in said chamber to control the flow of soda water to either one or the other of said passages, said valve comprising a washer bearing said last-mentioned closure means, a hole in said washer registering with a hole through said last-mentioned closure means, a rotatable controlling member passing through said holes and a rotatable handle connected therewith, a rotatable cover plate in said cylindrical chamber overlaying said washer and mounted on said rotatable controlling member for rotation therewith, said cover plate having a hole adjacent the wall of said cylindrical chamber, said hole being

normally positioned axially in said cylindrical chamber over a point between said spaced orifices, said hole and said spaced orifices being so positioned that on rotation of said handle and said controlling member in one direction said hole in said cover registers with one of said orifices and on rotation of said handle in the opposite direction said hole in said cover plate registers with the other of said orifices, and said conducting means for said soda water being connected to said cylindrical chamber adjacent the second of said closure means whereby the pressure of said soda water on said cover plate compresses said washer and the rotation of said handle controls the flow of soda water from said conducting means to said nozzle.

2. The combination of claim 1 further characterized wherein said rotatable controlling member is detachably connected to said rotatable cover plate, said connecting means including means to constrain said cover plate to rotate with said rotatable controlling member.

3. The combination of claim 1 further characterized wherein said rotatable controlling member is composed of two sections, said cover plate being connected to one of said sections, and detachable connecting means between said sections to constrain said sections and said cover plate to rotate together.

4. The combination of claim 1 further characterized by the provision of means to permit said cover plate to move axially to compensate for compression and wear of said washer.

5. The combination of claim 1 further characterized by additional elastic means to press said cover plate against said washer.

6. The combination of claim 1 further characterized by means to prevent said washer from turning with said cover plate and two holes in said washer registering with said orifices in said first closure means.

7. The combination of claim 1 further characterized by means to permit said cover plate to align its operating face with the face of said washer against which it presses.

8. The combination of claim 1 further characterized by means to cause said washer to turn with said cover plate and a hole in said washer which registers with the hole in said cover plate.

9. The combination of claim 1 further characterized wherein said washer is composed of a material capable of deformation under pressure.

10. A soda water faucet for soda water under pressure comprising a valve casing, a conducting means in said casing for conducting soda water to a generally cylindrical chamber therein, closure means for the ends of said chamber, a nozzle on said casing and two passages for conducting said soda water from said chamber to said nozzle, said passages terminating in two spaced orifices in one of said closure means, said spaced orifices being located adjacent the wall of said cylindrical chamber and said conducting means for said soda water being connected to said chamber adjacent the second of said closure means, a valve in said cylindrical chamber to control the flow of soda water from said chamber to one or the other of said passages, said valve comprising a washer bearing against the first specified closure means, a hole in said washer registering with a hole through said closure means, said hole in said closure means forming a bearing for a rotatable controlling member, a rotatable cover plate in said cylindrical chamber overlaying said washer

and mounted on said rotatable controlling member for rotation therewith, a rotatable handle connected with said rotatable controlling member exterior of said chamber and means to prevent any side thrust on said handle to misalign said rotatable controlling member in said bearing.

11. The combination of claim 10 further characterized by the provision of means to permit said cover plate to move axially to compensate for compression and wear of said washer.

12. The combination of claim 10 further characterized wherein the means to prevent said side thrust on said handle operating to misalign said rotatable controlling member comprises a second bearing for said rotatable controlling member spaced from said first-mentioned bearing.

13. The combination of claim 10 further characterized wherein the means to prevent said side thrust on said handle operating to misalign said rotatable controlling member comprises a bearing fixed to said valve casing, said bearing independently supporting said handle.

14. In a device of the character described, a casing provided with a pressure chamber having a radial wall and an outlet port in said wall; valve means in said chamber for controlling said outlet port, said valve means comprising a pivot journaled in the radial wall and projecting into

30 the chamber, said pivot mounted for rotation and having limited axial movement, a pressure plate spaced from and parallel to said radial wall abutting against the projecting end of the pivot and connected thereto for rotation therewith, said 35 plate rotatably and axially movable with the pivot and having an orifice positioned to align with said outlet port in one rotative position of the plate and adapted to move out of alignment therewith in another rotative position of the plate,

40 and a washer of inherently resilient material interposed between the pressure plate and said radial wall and having an opening positioned to effect communication between the orifice and port when the pressure plate is positioned to bring the same into alignment; means for rotatably actuating said pivot; and means for introducing fluid under pressure into the chamber behind said pressure plate, whereby fluid pressure in said chamber reacts against the pressure plate to move the same axially and compress the washer to seal said outlet port.

15. The combination of claim 14 wherein the connection between said pivot actuator means and said pressure plate affords a slight universal joint action.

16. The combination as set forth in claim 14 wherein the washer is of lesser area than the pressure plate.

17. The combination as set forth in claim 14 wherein oppositely acting spring means are arranged at opposite sides of the pivot-pressure plate assembly, the spring acting against the pressure plate being stronger than the spring acting against the pivot.

18. A faucet for controlling charged water at soda fountains and the like comprising a valve casing provided with a fluid pressure chamber having a radial wall and outlet ports for fluid under pressure in said wall, the ports being located substantially equidistant from the center thereof and spaced from each other; a valve in said chamber to control flow of soda water to one or the other of said ports, said valve comprising a deformable washer arranged so that the outer marginal portion thereof bears against said

radial wall, a rotatable pressure plate overlying said washer and movable axially thereagainst to compress the same, and means for rotating said pressure plate, the central portion of said washer being unsupported and the supported outer marginal portion thereof being of lesser area than the pressure plate whereby fluid pressure imposed on the total area of the pressure plate is applied against the supported outer marginal portion of said washer, a hole in said pressure plate positioned to register separately with said outlet ports and adapted to move out of register with all of said ports during rotation of said pressure plate.

19. The combination of claim 18 further characterized wherein said deformable washer is composed of leather impregnated with a waxlike material.

20. In a device of the character described, a casing provided with a pressure chamber having a radial wall and an outlet port in said wall; valve means in said chamber for controlling said outlet port, said valve means comprising a rotatable pressure plate in said chamber spaced from and parallel to said radial wall and having an orifice positioned to align with said outlet port in one rotative position of said plate and adapted to move out of alignment therewith in another rotative position of said plate, and a washer of inherently resilient material interposed between the pressure plate, cover plate and radial wall and having an opening positioned to effect communication between the orifice and the port when the pressure plate is positioned to bring the same into alignment, said radial wall and said washer being so formed that the washer does not support the central part of said pressure plate and the supported outer portion thereof being of lesser area than the pressure plate, whereby fluid pressure imposed on the total area of said pressure plate is applied against the supporting outer portion of said washer; a handle exteriorly of said pressure chamber; means connecting said handle and said pressure plate to cause said pressure plate to rotate with said handle; means in said connecting means to permit said pressure plate to press against said washer; and means for introducing fluid under pressure into the chamber behind said pressure plate whereby said fluid pressure in said chamber reacts against said pressure plate to compress the washer and seal the outlet port when said orifice is moved out of alignment with said outlet port.

21. In a device of the character described, a casing provided with a pressure chamber having a radial wall and an outlet port in said wall, a rotatable valve means in said chamber for controlling said outlet port, a rotatable handle exterior to said cylindrical chamber and means connecting said handle and said valve means to effect rotation thereof, said connecting means including a pivot member journaled in said radial wall and projecting in said chamber, said valve means comprising a rigid pressure plate within said chamber spaced from and parallel to said radial wall and overlying the projecting end of the pivot member and connected thereto for rotation therewith, said pressure plate having an orifice positioned to align with said port in one rotative position of said handle and adapted to move out of alignment therewith in a second rotative position of said handle and a washer of inherently resilient material interposed between the pressure plate and said radial wall surrounding said pivot member and covered by said pressure plate, said washer

having an opening positioned to effect communication between the orifice and the port when the pressure plate is positioned by said handle to bring the same into alignment, means for introducing fluid under pressure into said chamber behind said pressure plate and means in said connecting means between said pressure plate and said handle whereby said fluid pressure in said chamber acting against said pressure plate can move the same axially and compress the washer to seal the outlet port when said handle is moved to said second rotative position and said orifice is moved out of alignment with said port.

22. The combination of claim 21 further characterized by means to prevent any side thrust on said handle operating to misalign said rotatable pivot member in said journal.

23. The combination of claim 22 further characterized wherein said means to prevent misalignment of said rotatable pivot member comprises a second bearing for said rotatable pivot member spaced from said radial wall.

24. The combination of claim 22 further characterized wherein said means to prevent misalignment of said rotatable pivot comprises independent bearings for said handle mounted on said casing.

25. In a device of the character described, a casing provided with a pressure chamber having a radial wall and outlet port in said wall, a second pressure chamber having a radial wall and outlet port in said wall, valve means in said chambers for controlling said outlet ports, said valve means comprising rotatable rigid pressure plates in said chambers spaced from and parallel to said radial walls, a handle exterior to said chambers and means connecting said handle to said pressure plates for simultaneous rotation therewith, said pressure plates having orifices positioned to align with said ports in one rotative position of said handle and adapted to move out of alignment therewith in a second rotative position of said handle, and washers of inherently resilient material interposed between said pressure plates and said radial walls and covered by said pressure plates having openings positioned to effect communication between said orifices and said ports when the pressure plates are positioned by said handle to bring the same into alignment, means for introducing fluids under pressure into said chambers behind said plates and means in said connecting means whereby said fluid pressure in said chambers acting against said pressure plates can move the same axially and compress the washers, said radial walls, cover plates and washers being so formed that the washers do not support the central portions of said pressure plates, whereby the fluid pressure imposed on the total areas of said pressure plates is applied against the outer supporting portions of said washers to seal said outlet ports when said handle is moved into its second rotative position and said orifices are moved out of alignment with said ports.
